His Attorney.

UNITED STATES PATENT OFFICE.

ARTHUR PRIMROSE YOUNG, OF KENILWORTH, ENGLAND, ASSIGNOR TO GENERAL ELECTRIC COMPANY, A CORPORATION OF NEW YORK.

SOUND-REPRODUCING APPARATUS.

Application filed January 20, 1925, Serial No. 3,691, and in Great Britain February 20, 1924.

My present invention relates to electro-magnetic instruments employing pole-pieces which are themselves unpolarized, but are adapted to be magnetized by means of one or more permanent or electro-magnets. More particularly it relates to the manufacture of pole-pieces for such instruments and has for its object to provide a construction which is both simple and cheap to produce.

10 The pole-pieces hereinafter described are especially useful in the manufacture of electro-magnetic instruments such as telephone receivers.

My present invention broadly consists in 15 the provision of a pole-piece formed from a strip of suitable material which is bent into three planes, each approximately at right angles to one another. In making such a pole-piece from a flat strip, the strip may 20 be formed into a substantially L-shaped member by removing one of its corners (for instance, by punching out a portion including one of the corners) and the arms of the L-shaped member, or a portion of either arm 25 may then be bent each substantially through a right angle and on to the opposite sides of the middle portion of the L-shaped member. Two similar pole-pieces may be arranged with similar projecting portions adjacent to one another for carrying coils, the 30 other projecting portions, respectively, lying against the poles of one or more permanent or electro-magnets.

My invention will best be understood by 35 reference to the following description taken in connection with the accompanying drawing in which Figs. 1 to 4 illustrate the various steps which may be taken in the construction of pole pieces in accordance with 40 my invention; and Fig. 5 is a top plan view of the telephone receiver with the diaphragm, cover and coils removed.

In the construction of pole pieces in accordance with my invention, two similar rectangular portions 11, as indicated in Fig. 1, 45 may be punched out from the corners at the end of one of the sides of a substantially rectangular strip of suitable material, such as soft iron or mild rolled steel. A third 50 and preferably smaller rectangle 12 may be punched out from the middle of the projecting portion 13 of the strip remaining between the two cut-away rectangles 11. The two projecting portions 13 thus formed may 55 then be bent at right angles to the original

plane of the strip. It should be noted that the operation so far described can be accomplished at each stroke of a suitably designed power press, and Fig. 1 shows the shape at this stage. After this, the ends 14 of the strip 60 may be bent downwards at right angles to the strip and on the other side from which the middle portions 13 project, this being shown in Fig. 2.

Next the strip may be divided into two 65 similar portions, forming thereby two similar pole-pieces. These pole-pieces may then be arranged with their similar projecting portions 14 adjacent to and spaced from one another and they may be clamped in this 70 position by means of a member 15 of non-magnetic material, such as brass, which may be riveted thereto, as is shown in Fig. 3 or 4. This insert may then be placed in a mould, together with a composite insulating 75 material, which may be moulded to hold the pole-piece permanently in position and to form the body and casing 16 of the instrument. A slot or groove 17 may be formed in the mass of insulating material with its 80 ends adjacent to the anchoring portions 13 of the pole-pieces for the subsequent insertion of a permanent magnet 18 of cobalt steel or any material having strong magnetic properties, the magnet being retained in 85 position by means of a set screw 19 or other clamping means. This arrangement is shown in Fig. 5. Alternatively, before the insert is placed in the moulding, the permanent magnet, which may be a bar arranged 90 alongside of, or a curved magnet with its ends passing under the middle portion of each pole-piece, may be clamped in position with its poles adjacent the projecting portions 13 on the pole-pieces and the whole then subjected to the moulding operation, previously described, the groove 17 being, of course 95 omitted.

According to another method of construction the pole-pieces, before the strip has 100 been divided into two similar pole-pieces, two or more strips may be placed in line and in a similar sense (for instance, with the ends 14 of each strip all projecting downwards), each strip being spaced from 105 its adjacent strip or strips a predetermined amount. A flat strip or angle member of non-magnetic material may then be placed upon and riveted to each pair of adjacent strips so as to hold them firmly in spaced 110

- relation to one another. Or a continuous member of non-magnetic material may be placed along and riveted to the original strips. It now remains to divide each of the original strips in half, which leaves a number of pairs of pole pieces suitably spaced and fixed with respect to one another, the outside ends of the two outside strips being waste metal. Each pair of pole pieces may then be attached to a magnet and or placed in a mould together with a composite insulating material which may be moulded to embed a portion of the magnetic structure.
- 15 Finally, suitably wound coils, which for convenience of illustration are not shown on the drawing, may be placed upon and secured to the poles 14 and their ends may be connected to terminals 20 adapted to screw into the insulating material and to be attached to the main leads.
- What I claim as new and desire to secure by Letters Patent of the United States is:—
1. A pole piece for an electro-magnetic sound reproducing device consisting of a strip of magnetic material having three portions extending in three planes which are approximately at right angles to each other, two of said portions extending in opposite directions from the third portion, one of the oppositely extending portions providing a core on which a winding may be supported and the other an anchoring means for the pole piece.
  - 35 2. A telephone receiver which comprises a pair of pole pieces each consisting of a strip of magnetic material having three portions extending in three planes which are approximately at right angles to each other, each of said pole pieces having one portion embedded in a mass of insulating material and another portion projecting from the mass of insulating material.
  3. A telephone receiver which comprises a pair of pole pieces each consisting of a strip of magnetic material having three portions extending in three plane which are approximately at right angles to each other, each of said pole pieces having one portion embedded in a mass of insulating material and another portion projecting from the mass of insulating material, and a permanent magnet having its poles adjacent the embedded portions of the pole pieces.
  4. A telephone receiver which comprises a pair of pole pieces each consisting of a strip of magnetic material having three portions extending in three planes which are approximately at right angles to each other, each of said pole pieces having one portion embedded in a mass of insulating material and another portion projecting from the mass of insulating material, a slot in said mass of insulating material, and a permanent magnet located in said slot and having its poles adjacent the embedded portions of the pole pieces.

In witness whereof, I have hereunto set my hand this 31st day of December 1924.

ARTHUR PRIMROSE YOUNG.
